UNITED STATES PATENT OFFICE.

FRED A. RUNDLE, OF HARVEY, ILLINOIS.

HOISTING MECHANISM.

1,195,270.

Specification of Letters Patent. Patented Aug. 22, 1916.

Application filed March 15, 1915. Serial No. 14,589.

To all whom it may concern:

Be it known that I, FRED A. RUNDLE, a citizen of the United States, residing at Harvey, in the county of Cook and State 5 of Illinois, have invented a certain new and useful Improvement in Hoisting Mechanism, of which the following is a specification.

This invention relates to automatic 10 brakes, particularly to brakes for use on cranes and other hoisting apparatus.

The object of this invention is to provide a brake which, while noiseless, is exceptionally positive in action.

15 The invention consists in a device capable of carrying out the foregoing objects, which can be easily and cheaply made and installed, which is satisfactory in operation and not readily liable to get out of order.

20 It consists more particularly in a means for operating the brake ratchet dog in which the strain on all of the parts used in operating it is in one common plane, thereby doing away with torsional or bending 25 strains which have frequently been present in prior devices.

The invention further consists in a novel 30 mounting for certain of the parts, thereby greatly simplifying the construction and 35 operation, all as will fully appear in the specification and claims.

Referring to the drawings in which similar numerals indicate the same parts throughout the several views, Figure 1 is a 35 side view of a trolley in an ordinary traveling crane, having the devices of this invention applied thereto in its preferred form. Fig. 2 is a plan view of certain parts of the device of Fig. 1 which embody the essential 40 features of this invention. Fig. 3 is a detail side view of the ratchet operating device. Fig. 4 is a vertical sectional detail view through shaft A of Fig. 1.

The crane trolley to which the invention 45 is applied is supported by the shafts 10 on the wheels 12 and has any suitable form of standard frame 14 carrying shafts 15, 16, 17 and 18, the former being the power shaft, driven by a suitably located motor, and the 50 latter the load shaft. On this load shaft 18 is the winding drum 20 over which opposite ends of the load carrying rope or chain 22 pass. The middle of this load carrying member 22 passes over the suitably mounted 55 adjusting pulley 24 and the pulley 26 to whose shaft 27 the lifting hook 28 is at-

tached. As is usual in this art, the driving shaft 15 carries a small pinion 30 meshing with gear 32 on shaft 16 which shaft in turn carries pinion 34 meshing with gear 38 on shaft 17, which latter shaft carries pinion 40 meshing with gear 42 on shaft 18, the result being that when shaft 15 is driven by any suitable means, such for instance, as an electrical motor (not shown) engaging 65 with wheel 43 on said shaft 15, the load carrying drum 20 is rotated at considerably reduced speed.

The problem of this invention is to provide a brake device which will, during the 70 operation of raising the load, automatically lock the load in any position at which the motor may be stopped either accidentally or intentionally, at the same time permitting the motor to be actually operated 75 to lower the load when the operator desires to do so and at the same time arrange this device so that it works both positively and noiselessly and occupies little space. This 80 result is accomplished by installing between the gears 32 and 40 and the gears 34 and 38 heretofore described, the simple device illustrated in Figs. 3 and 4.

The shaft 17, heretofore referred to, is 85 provided with a pinion 40 and an adjacent disk 44 rigidly secured together and to the shaft by any suitable means so that they rotate positively with the shaft. The portion of shaft 17 immediately adjacent to disk 44 is provided with screw threads 46 90 as clearly appears in Fig. 4 on which the gear 38 is adapted to travel longitudinally of the shaft between narrow limits. Loosely mounted on the shaft 17 is placed a nut or equivalent device 60 rigidly securable in position by any suitable means and of such a size and shape that it limits the amount of travel of the gear 38 longitudinally of the shaft 17 upon the gear threads 46. This 95 positive movement of the gear 38 under the conditions just mentioned is sufficient so that in one position the ratchet wheel 50 is not bound by the friction plates 54 and 56 and in the other position it is gripped by those plates between the disk 44 and the gear 38 so that the disk, ratchet wheel and gear rotate in unison.

Journaled on a shaft 62 provided for the purpose and suitably supported by any suitable means, as for instance, the outer walls 110 of the case 64 which inclose the entire trolley gearing mechanism, is the ratchet dog

- 66 adapted to selectively mesh with the teeth 52 on ratchet wheel 50. Pivotedly connected at 68 to this ratchet dog 66 is a link 70 in turn connected at 72 to a collar 74 rotatably mounted upon shaft 16. This collar is made in two parts, as shown, pivoted together at 76 on one side of the shaft and spring pressed together on the opposite side of the shaft through the agency of the 5 coiled spring 78 on bolt 80 passing through the two parts of the collar as clearly appears in Fig. 3. The parts just described are so proportioned that this collar 74 engages the shaft 16 with just sufficient friction so that 10 when shaft 16 rotates in a clock-wise direction, as viewed in Fig. 3, the link 70 will be moved downward with the result that the ratchet dog 66 is forced into engagement with an adjacent ratchet tooth 52 and that 15 as soon as this occurs the shaft 16 then rotates freely in collar 74;—also, that as soon as shaft 16 begins to rotate in a counter clock-wise direction, the friction of the collar 72 on shaft 16 is sufficient to pull link 20 70 upward with sufficient force to withdraw ratchet dog 66 from ratchet teeth 52 after which the shaft 16 rotates as before.
- It will be noted that shaft 16 is, under the system of gearing set forth, one which rotates much more rapidly than shaft 17 with the result that the movements of dog 16 are made much more rapidly and sharply than they would be were the collar 74 applied to shaft 17 or some other one rotating at its 25 speed. It will also be noticed that the collar 74 and the dog 66 and connecting parts all lie in the same vertical plane thereby first economizing space and second doing away with the torsional strains which have 30 existed heretofore in mechanism of this class where the ratchet operating device and the ratchet dog itself are in remotely separated parallel planes.
- In the operation of the device, power is 35 applied to shaft 15 and load is attached to the hook 28. The power shaft is rotated in the direction indicated by the arrow thereby rotating shaft 16 in the direction indicated by its arrow thereon, thereby at once with- 40 drawing ratchet dog 66 from engagement with ratchet teeth 52. This rotation of shaft 16 acts through pinion 34, gear 38 and shaft 17 to rotate pinion 40 on shaft 17 thereby causing screw threads 46 on said shaft 45 to travel into the hub 46 of gear 38 to ultimately lock disk 44 with gear 50 and gear 38 rigidly together. As soon as this takes place, which it does momentarily, the motion of the motor is transmitted to shaft 18 and the 50 lead is raised. When the power motor is stopped, the load on the hook 26 tends to reverse the direction of motion of all of the respective shafts including shaft 16 and this, in the manner heretofore described, 55 immediately causes the dog 66 to be thrown into engagement with ratchet teeth 50, thereby positively locking the load at the point where the motor stopped. When it is desired to lower the load, power is applied to the shaft 15 and is rotated in the direction opposite to the arrow thereon. This movement of the shaft 15 causes the screw threads 46 to move out of the hub 46 of gear 38 thereby releasing the clutch produced by the friction disks 54—56 on ratchet wheel 50 and therefore the weight of the load on 60 26 can, in the ordinary manner, rotate the gearing to which it is attached until this clutch is again locked, in other words, until the load has caught up with the movement 65 of the motor.
- The construction shown in Fig. 4 of mounting the gear 38 and screw threads cut directly upon the shaft has the distinct advantage of simplifying the original construction in reducing the number of parts required and the amount of probable 70 pairs.
- Having thus described my invention, what I claim as new and desire to secure 75 by Letters Patent, is:
1. A clutch device comprising a shaft having a stationary flange thereon, a member loose on the shaft to be clamped to the flange and a wheel having its hub screw threaded directly upon the shaft movable into and out of engagement with said last mentioned member and means for moving said wheel for the purposes set forth.
  2. A clutch device comprising a shaft having a stationary flange thereon, a member loose on the shaft to be clamped to the flange, a wheel having its hub screw threaded directly upon the shaft to move into and out of engagement with said last mentioned member, means for moving said wheel and means limiting the amount of movement on said shaft away from said flange for the purposes set forth.
  3. In a device of the class described, the combination of two parallel shafts, gearing uniting said shafts, a ratchet wheel on one of said shafts, a ratchet dog pivoted independently of both of said shafts engageable with said ratchet wheel to stop it and its shaft, a collar rotatably but frictionally engaging the second shaft and a connection between said collar and the ratchet dog, the wheel, collar and connecting parts mentioned being in substantially the same plane transverse to the shafts for the purposes set forth.
  4. In a device of the class described, the combination of two parallel shafts, intermeshing gears of different sizes on the two shafts, a ratchet wheel on one of said shafts, a ratchet dog pivoted at a point outside the axis of said shafts engageable with said ratchet wheel to stop it and its shaft, a collar rotatably but frictionally engaging the sec-

ond shaft and a connection between said collar and the ratchet dog, the wheel, collar and connecting parts mentioned being in substantially the same plane transverse to 5 the shafts for the purposes set forth.

5. In a device of the class described, the combination of two parallel shafts, intermeshing gears of different sizes on the two shafts, a ratchet wheel on one of said shafts 10 carrying the larger of said gears, a ratchet dog pivoted at a point outside the axis of said shafts engageable with said ratchet wheel to stop it and its shaft, a collar on the second shaft rotatably but frictionally engaging the second shaft and a connection between 15 said collar and the ratchet dog, the wheel, collar and connecting parts mentioned being in substantially the same plane transverse to the shafts for the purposes set forth.
6. In a device of the class described, the combination of two parallel shafts, a pair of intermeshing gears lying in the same plane and mounted respectively upon said 20 two shafts, another pair of non-intermesh-

ing gears also mounted upon said shafts but lying in another plane parallel to and slightly remote from the plane of the first mentioned gears, a ratchet wheel on one of said shafts lying in the space between the 30 two planes of the gears, means for detachably connecting said ratchet wheel to the shaft on which it is located, a ratchet dog pivoted at a point outside the axis of said shafts suitably mounted to detachably engage and stop said ratchet wheel and means connected to said ratchet dog rotatably but frictionally engaging the shaft opposite to the one on which the ratchet wheel is mounted, these last mentioned parts lying in the 40 same plane as the ratchet wheel and between said respective planes of the gears for the purposes set forth.

In witness whereof, I have hereunto subscribed my name in the presence of two witnesses. 45

FRED A. RUNDLE.
